UNITED STATES PATENT OFFICE.

WILLIAM SMITH, OF SPRINGDALE, ARKANSAS.

CHURN.

SPECIFICATION forming part of Letters Patent No. 768,633, dated August 30, 1904.

Application filed August 25 1903. Serial No. 170,732. (No model.)

To all whom it may concern:

Be it known that I, WILLIAM SMITH, a citizen of the United States, residing at Springdale, in the county of Washington and State of 5 Arkansas, have invented certain new and useful Improvements in Churns; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention is a churn; and it consists of 15 a base on which rests the churn-pail and from one end of which rises a vertical frame to which is hinged a horizontal frame carrying two pulleys around which works a belt operated by a lever, and from one of these pulleys 20 extends downwardly a hollow arm in which is secured the handle of the dasher.

The minor details of the invention are described in the specification.

The object of my invention is to produce a 25 churn which may be cheaply manufactured and easily operated, the lid of which may be easily and quickly raised, so that the condition of the milk may be examined, and that will prevent the milk from splashing out.

30 In the accompanying drawings, Figure 1 is an elevation of my invention, partly in section, the lid down. Fig. 2 is an elevation, partly in section, the lid up. Fig. 3 is a detail view showing the upper part of the dasher 35 and the means by which it is secured to its pulley. Fig. 4 is a detail view showing the lever, the ends of the belt passing through a perforation and secured. Fig. 5 is a detail showing the upper end of the posts in which 40 the lower rail of the horizontal frame rests. Fig. 6 is a detail view of part of the lever 17 and belt 20, showing another means of regulating the tension of the belt.

My invention is described as follows:

45 The numeral 1 represents the base of the frame; 2, the churn-pail seated on the end thereof; 3, the vertical frame rising from the other end of the base. This frame is properly braced and has across its center midway between top and bottom a bearing-beam 4.

The right-hand standard 5 of said frame 3 is taller than the left-hand standard 6. Secured horizontally on the upper end of the standard 6 is a beam 7, its right-hand end being mortised into the standard 5 a short distance below its upper end. Hinged to the left-hand end by a butt-hinge 8 is a horizontal frame 10, consisting of an upper beam 11, a lower beam 12, and a central block 13. These two beams 11 and 12 are secured one to the upper 55 face and the other to the lower face of said block on parallel lines. Running vertically through the ends of these beams are perforations 14, the lower perforations registering with the upper ones, and journaled in these 60 perforations are pulleys 15 and 16. Hinged to said bearing 4 is a lever 17, its upper end extending some distance above the horizontal frame 10 and bearing in said upper end a handhold 18. Said lever is made somewhat 65 wider near its center than at each end, and through the wide part of said lever is a perforation 19, through which is drawn the free end of the belt 20. One end of this belt 20 is secured to the face of the lever 17 by a 70 staple 21. Below the perforation 19 and slightly to the right thereof is another perforation, 22, and below the perforation 22 and slightly to the right thereof is another perforation, 23. Fitting in one of these perforations is a pin 24. The purpose of these two or more last-mentioned perforations and pin 75 is to regulate the tension of the belt.

When the belt is drawn around the pulleys 80 and its end 21 secured as shown, its other end, 25, is drawn through the perforation 19 and down straight, as indicated by the dotted line 26. If the belt becomes a little loose, I push this end over to the right and insert the pin in the middle hole 22, and if after a little use 85 the belt becomes loose again I push this end of the belt over to the right beyond the hole 23 and insert the pin in said hole; but should the belt become too tight from any cause, weather or otherwise, after having been 90 pushed over to the last-mentioned hole 23 I remove the pin back to the left one, (hole,) or I may remove it entirely and let the belt resume its normal straight line 20. Thus it will be seen how quickly and easily the tension of 95 100

the belt may be regulated simply by moving the pin; but should the belt stretch so much that the moving of the pin may not be sufficient to regulate its tension I loosen the staple 27 5 and draw the end of the belt down a little and secure it.

The spindle 28 of the pulley 16, journaled over the churn-pail, has secured to its lower end a sleeve 29.

10 Fig. 6 shows another method of regulating the tension of the belt. In this method one end 21 of the cord is secured by a staple, and below this end of the cord are a number of perforations through the lever, one below the other, the pin 24 being adapted to fit in either one of the perforations. The free end of the cord is drawn through the perforation 19 and down around the pin 24, which is in the upper perforation, and then up, forming a loop. 15 To tighten the tension of the cord, I move the pin down from perforation to perforation as required. 20

The churn-dasher 30 consists of two perforated arms 31, the upper ends of which are 25 secured to a body 32. Extending above the body is a neck 33, which a short distance from the body is made smaller, leaving a shoulder 34. Fitting around the smaller and upper part of the neck 35 and down against the 30 shoulder 34 is a washer 36. The upper face of this washer fits against lid 37 of the churn and keeps the milk from splashing out through the perforation in said lid. Passing horizontally through the sleeve 29 is a pin 29'. The 35 smaller part of the neck 35 has in its upper end a V-shaped depression, leaving two vertical extensions 35². The said pin 29' fits in this V-shaped depression, and consequently when the spindle 23 of the pulley 16 is 40 revolved the neck 35 and the dasher 30 are necessarily revolved. Passing through the lower end of the sleeve 29 and the upper end of the neck 35 are perforations concentric with each other, and passing through these perforations 45 is a cotter-pin 38, which holds the sleeve 29 to the neck 35.

Figs. 1 and 2 show an edge view of the right-hand standard 5 of the frame 3.

Fig. 5 shows a face view of the upper end 50 of the standard 5. In the upper end of this standard 5 is cut a slot 39, leaving a vertical spring 40. To the other edge of the standard is secured a cleat 42. This spring 40 and cleat 42 extend a little way above the standard 5, so that when the frame 10 is down the lower beam thereof rests on the upper end of said standard and is bound between said spring and said cleat. The tension of said spring 40 is regulated by a thumb-screw 41.

60 When I desire to examine the condition of the milk in the churn-pail, I raise the forward end of the frame 10, which brings up with the churn-lid washer and dasher, and when I let the frame down again it is clamped between 65 said cleat and spring. To prevent the frame

10 and lid 37 from being raised too high, I attach one end of a strap 43 to the standard 5 and the other end to the beam 12, so that when the frame 10 is down the said strap hangs loose in the form of the letter S; but when said frame is up said strap is taut. 70

Having described my invention, what I claim as new, and desire to secure by Letters Patent, is—

1. A churn, consisting of a base 1; a churn-pail 2, seated on said base; a vertical frame 3, rising from said base; a horizontal frame 10, hinged to said base, and having pulleys 15 and 16, one journaled to each end; a belt 20, working around said pulleys; a lever 17, 75 hinged to said frame 3, and adapted to operate said belt; a sleeve 29, extending downwardly from the spindle of the pulley 16 below said horizontal frame and revolving above the churn-pail; a dasher 30, adapted to revolve in said churn-pail; a neck 33, extending up through the perforation in the lid of said churn; a washer 36, fitting on smaller part 35, of said neck 33, and against the lower face of the churn-lid; said neck 35, fitting in sleeve 80 29, and provided with two upward extensions 35²; and a pin 29', passing through said sleeve 29, and between said extensions, with means to regulate the tension of the belt, substantially as shown and described, and for the purposes set forth. 85

2. In a churn, substantially as shown and described, having a base 1, a churn-pail seated on said base, a vertical frame rising from said base, a horizontal frame hinged on the upper end of said vertical frame and carrying the dasher and operating means thereof, the inner standard 5, of the vertical frame being taller than the outer standard 6; a spring 40, integral with and extending from one edge and above 100 the upper end of said standard; a thumb-screw 41, regulating the tension of said spring, and a cleat 42, secured to the opposite edge of said standard, the lower rail 12, of the frame 10, adapted to rest on the upper end of said standard and between the cleat 42, and the spring 40, substantially as shown and described, and for the purposes set forth. 105

3. In a churn, substantially as shown and described, having a base 1, a churn-pail seated 115 on said base, a vertical frame rising from said base, a horizontal frame hinged on the upper end of said vertical frame and carrying the dasher and operating means thereof, the inner standard 5, of the vertical frame being taller 120 than the outer standard 6; a spring 40, extending from one edge and above the upper end of said standard; a thumb-screw 41, regulating the tension of said spring; a cleat 42, secured to the opposite edge of said standard, the lower rail 12, of the frame 10, adapted to rest on the upper end of said standard and between the cleat 42, and the spring 40; and a strap 43, having one end secured to the standard 5, and its other end to the beam 12 pre- 130

venting said horizontal frame from being raised too high, substantially as shown and described, and for the purposes set forth.

4. In a churn, substantially as shown and described, a lever 17, hinged to the vertical frame, and adapted to operate the pulley-belt 20, said lever provided (near its center and enlarged portion) with a central perforation 19, and below and to the right of said central 10 perforation, a perforation 22, and below and to the right of said perforation 22, another perforation 23, and a pin 24, adapted to fit in either of said last two mentioned perforations, substantially as shown and described, and for 15 the purposes set forth.

5. In a churn, substantially as shown and described, having a vertical frame 3, rising from a base; a horizontal frame, carrying pulleys, hinged at one end to one side of said horizontal frame, and a strap 43, having one end secured to the center post of said frame, and its other end to the other end of said horizontal frame, substantially as shown and described, and for the purposes set forth. 20

In testimony whereof I affix my signature in 25 presence of two witnesses.

WILLIAM SMITH.
